UNITED STATES PATENT OFFICE.

MATHEW F. DEEGAN, OF CHICAGO, ILLINOIS, ASSIGNOR OF ONE-HALF TO
HENRY HOOPER, OF SAME PLACE.

CONSTRUCTION AND VENTILATION OF SANITARY DEVICES, &c.

SPECIFICATION forming part of Letters Patent No. 270,761, dated January 16, 1883.

Application filed September 13, 1882. (No model.)

To all whom it may concern:

Be it known that I, MATHEW F. DEEGAN, a citizen of the United States, residing at Chicago, in the county of Cook and State of Illinois, have invented certain new and useful Improvements in the Ventilation of Sanitary Devices, &c.; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

15 My invention has reference to an improved means for ventilating sinks, basins, baths, closets, urinals, &c.

The object of the invention is to produce and maintain an active draft in closets, &c., which 20 drives out all offensive odors and keeps the fixtures and surrounding atmosphere pure and odorless.

I provide a means for introducing fresh air from the exterior of the building into a space 25 where the impurities, odors, gases, &c., are accumulated, and for circulating the air therein, and then conveying it away in ventilator-pipes which lead upward. By the same system of piping in which the air is introduced 30 for ventilating purposes the overflow from the various fixtures is taken care of and conveyed away. I am enabled to dispense with traps and other sealing devices, and use a plain waste-pipe, which greatly facilitates the rapid 35 movement and escape of all matter passing into it.

The accompanying drawings illustrate what I consider the best means of carrying out the invention.

40 Figure 1 is a section of a room, showing a bath-tub, closet, and basin with my devices applied, a part of the casing of the several parts being removed to show the construction and arrangement. Fig. 2 is a section of the 45 same on the line $x-x$, looking in the direction indicated by the arrow.

Similar letters of reference indicate corresponding parts in all the figures.

I have shown three appliances—a bath-tub, 50 a closet, and a basin or sink—to indicate the

general adaptability of my invention to such uses. It will be understood, however, that the invention may be applied to any one of them separately, or to two of them or a series of any one variety, to urinals or a series of such, and to all constructions needing ventilation to carry off offensive smells and deleterious gases. 55

H is a section of a room or apartment in which the fixtures are placed. A is the bath-tub, B the closet, and C the basin. 60

W is the waste-pipe, which carries off the water and other matter from the fixtures. It has connections to each of them, and is a plain pipe without trap or other sealing contrivance. At proper points in its length between the 65 bath-tub and closet and between the basin and closet stop-cocks w are provided, which close the pipe W tightly and prevent the escape of odors from the closet-connection to the bath-tub and to the basin. As shown in the drawings, one of the cocks is situated in the waste-pipe near the bath-tub, and the other in the waste-pipe on the other side of the closet to prevent the gases reaching the bath-tub and basin. 70

75 It will be understood that the fixtures A B C are fitted with a water-supply in any usual or suitable way. They have overflow-passages $a b c$, which discharge as hereinafter set forth.

The ventilator-pipes D' D² D³ are constructed 80 with widened mouths, and arranged to receive the air and its impregnating-gases from each of the fixtures A B C and deliver it into the common uptake D, which discharges it into the atmosphere above the house. The construction and ramification of these ventilator-pipes 85 are varied according to the different situations in which they are used. When the closet or any other one of the fixtures is used alone the lateral branches will be dispensed with and 90 the straight uptake and the branch, which is practically a continuation of it, only used. The suction caused by the upward tendency of the gases in the ventilator-pipes is aided by an active circulation in the parts to be ventilated, 95 which is created by the joint operation with the ventilator-pipes of an air-induction pipe, E. This pipe E is provided with an entrance-branch, E⁴, from the exterior of the building, and discharge-branches E' E² E³ at the bath, 100

closet, and basin, respectively. The entrance-pipe on the exterior of the building is provided with a draft box or cap, F. Fresh air from the outside atmosphere is thus brought in through the piping E⁴ E' E² E³ and delivered to the desired points. The exits from these pipes at such points are so arranged with reference to the openings of the ventilator-pipes D', &c., as to cause the air they deliver to travel through the space into which they open and become thoroughly charged with the gases and odors therein contained before being caught up and carried away by the ventilator-pipes, thus taking up and driving out all the noxious odors and gases. Ordinarily these exits will be above the entrances to the ventilator-pipes, so that the discharge of the fresh air into the higher portions of the spaces to be ventilated will dislodge and start into movement the gases accumulated there and present them to the ventilator-pipe to be carried off.

The trap or other sealing device which is the occasion of so much annoyance from choking and the giving off of gases from the load that will lodge in it, particularly when the flow of water is not very strong, is dispensed with. The plain waste-pipe facilitates and insures the speedy and complete removal of all matter which enters it, and with much less flow of water than when a trap is used.

The air-supply pipe E performs a twofold function. The first has already been described in connection with the ventilation of the fixtures. The second is also important, and is that of receiving the overflow from the several receptacles when, by accident or otherwise, they become overfilled, as in the case of the bath or basin, by allowing the faucets to run too long when the cocks w are closed. The openings of the pipe E at the several points, like the ends of the ventilator-pipes, are provided with funnel-shaped mouths, and are, as will be observed, located directly under the overflow-passages a b c, respectively, so that when the water rises so high in the receptacles as to flow out through these passages it will be caught by the mouths of the pipe E, carried off, and discharged through the entrance-pipe E⁴ into the outside air. The water which is ordinarily thus discharged is pure and inoffensive; but a suitable arrangement to carry it to the sewer may be provided. The entrance-branch E⁴ may be led to any desired point before it is cut

off, so that the discharge of the overflow-water will be at a convenient place. Care, however, should be taken to have the situation such as will offer no obstacle to a steady and ample supply of pure air.

When the receptacles are overflowing no gases or odors are usually perceptible, so that the use of the pipe E for this purpose does not interfere with its function as a promoter of ventilation.

When so desired, even where the ventilator-pipes from several fixtures all discharge into one common uptake, as shown in Fig. 1, a separate air-supply pipe having an entrance, E⁴, and draft-box F may be placed upon each fixture.

The mouths of the air-pipe E being entirely disconnected from the other pipes, the opportunity for counter-currents, and the consequent destruction of its efficacy, is obviated.

As already indicated, I do not confine myself to the details shown in the drawings.

I have shown the several receptacles grouped, as they frequently are in residences.

The principle involved in this invention is applicable to all varieties of sanitary constructions, and the method of ventilation equally effective, whether one or more of the fixtures be used.

The funnel-shaped mouths may be dispensed with; but they increase the efficacy of the pipes.

What I claim is—

1. A closet or other sanitary construction with a trapless waste-pipe having cocks, as described, in combination with an air-duct bringing fresh air into the space to be ventilated, said air-duct being formed with a free mouth disconnected from the apparatus, so as to obviate the liability of counter-currents, and of a ventilating-pipe for receiving and conveying away the foul air, as herein set forth.

2. The combination, with the commode, bath, basin, or similar fixtures and a trapless waste-pipe, of the stop-cocks w w for shutting off the communication between the several fixtures and ventilating-pipes, substantially as described.

In testimony whereof I affix my signature in presence of two witnesses.

MATHEW F. DEEGAN.
